(57) **CLAIM**

The ornamental design for a portable air cleaner holder, as shown and described.

DESCRIPTION

1. Portable air cleaner holder

1.1 : Perspective

1.2 : Rear perspective view

1.3 : Front

1.4 : Back

1.5 : Left

1.6 : Right

1.7 : Top

1.8 : Bottom

1.9 : Perspective view of the air cleaner holder in use holding a portable air cleaner. The portable air cleaner is shown in broken lines and is not part of the claimed design.

1 Claim, 9 Drawing Sheets(56)
